UNITED STATES PATENT OFFICE.

WILLIAM SHERWOOD FISKE, OF BROOKLYN, NEW YORK, ASSIGNOR TO THE
HOPKINS & DICKINSON MANUFACTURING COMPANY, OF SAME PLACE.

LOCK.

SPECIFICATION forming part of Letters Patent No. 399,026, dated March 5, 1889.

Application filed September 1, 1887. Serial No. 248,519. (Model.)

To all whom it may concern:

Be it known that I, WILLIAM SHERWOOD FISKE, a citizen of the United States, resident at Brooklyn, in the county of Kings and State 5 of New York, have invented certain new and useful Improvements in Cylinder-Locks; and I do declare the following to be a full, clear, and exact description of the invention, such as will enable others skilled in the art to which it app- 10 pertains to make and use the same, reference being had to the accompanying drawings, and to letters or figures of reference marked thereon, which form a part of this specification.

Figure 1 is a bottom view of lock-ease A, with casing 46 in place. Fig. 2 is a bottom view of cylinder-lock with slide 42 in unlocked position. Fig. 3 is a side elevation of cylinder-lock. Fig. 4 is a top view of cylinder-lock. Fig. 5 is a side elevation of cylinder-lock with casing 46 removed, broken away, showing pin 53 and spring 54. Fig. 6 is a side elevation of cylinder-lock, casing removed, with piece 150 removed, and ends of tumblers 25 k k' k'' broken away, showing springs m m' m'' , and also springs t t' . Fig. 7 is a top view of cylinder-lock with casing 46 removed. Fig. 8 is a top view of revolving cylinder with springs and tumblers removed. Figs. 9 and 30 10 are detail side elevations of tumblers. Fig. 11 is a detail top view of piece 150. Fig. 12 shows the lock and mechanism to which the cylinder-lock is applied.

The invention relates to improvements in 35 cylinder-locks and novel combination of parts, as hereinafter set forth.

The object of my invention is to provide a night-latch lock to be used in combination with and acted upon by certain parts of a mortise-lock, for which separate application 40 for Letters Patent has been made under even date and numbered 248,520, a portion of which is illustrated in Fig. 12 herewith, but not claimed in this application, and, further, 45 to provide a night-latch lock that will operate the latch and lock-bolts of the mortise-lock without it being necessary to use the knob connected with said mortise-lock.

Referring by letter and numerals to the ac- 50 companying drawings, 46 represents the cyl-

inder-case, provided in its outer face with the central circular opening, 47, through which the key is introduced into the revolving plug hereinafter explained. The cylinder-case is provided on its inner edge with the lip or 55 flange x , by which it is secured in the opening y of the mortise-lock case. The central circular opening, 47, of the cylinder-case is provided with the radiately-disposed recess 50, with which the slot 51 in the removable 60 plate 52' on the outer end of the revolving plug 49 registers. Said plug 49 is provided with a seat or pin-hole, 52, opposite the open end of the slot 51 in the plate 52' for the reception of a shouldered or headed locking-pin, 65 53. 54 is a spiral spring which encircles the pin 53, and bears against a shoulder, 56, in the seat or pin-hole 52 and against a shoulder, 55, of the pin 53, and tends normally to project the pin into the recess 50, and thereby 70 locks the plug 49 and prevents it from being turned until the pin 53 is pushed in by the proper key having a projecting lip that will engage said pin.

The revolving plug 49 is provided with five 75 tumblers, K K' K'' K^3 K^4 , notched transversely at their inner ends, the tumblers K' and K^3 notched as at c , and the tumblers K , K'' , and K^4 notched as at d' . These tumblers are also provided with arms at their outer ends. The 80 arms l of the tumblers K' K^3 are on the same side as the notches c , while the arms m of the tumblers K , K'' , and K^4 are on the opposite side of the notches d' . These tumblers are held in their normal position in the revolving 85 plug by spiral springs m and t' , said springs bearing against the inner edges of the arms l and m of the tumblers. These tumblers are placed in the revolving plug so that the notches c and d' are on the same side. 90

Short parallel longitudinal integral ribs a and a' extend to the face of the seat n of the plate 52', and between them and the sides thereof parallel longitudinal grooves q q' q'' are formed, in which the springs m' work. 95 The tumblers K' and K^3 work in grooves s and s' of a removable side piece, 150, and are held in their normal position by the spiral springs t' , seated in depressions u and u' in the body of the plug. The revolving plug is 100

provided on its inner face with a sliding plate, p , said plate being provided with a projecting lug, p' , and a rectangular opening, p^2 . 49^2 is a projecting arm or stud on the inner face of the revolving plug, for a purpose hereinafter explained.

To operate the mortise-lock with the cylinder-lock, place the key in the slot 51, and by pressing the key inward the tumblers are depressed. The notches c d' are then opposite one edge of the rectangular opening in the sliding plate p . By turning the key, which will turn the revolving plug, the lug on the sliding plate is brought in contact with the eccentric flange y^3 , formed on the case of the mortise-lock, and forces the plate p to engage the notches c and d' , and thus hold them while operating the mortise-lock. By continuing to turn the key the arm 49^2 enters the notch O^2 of the lock-bolt stem 18 of the mortise-lock and forces said bolt into its keeper. As the bolt is projected the slotted sliding fence 7, by means of the spring 18 ^{2} , forces the bent end 6 of said fence into recess 5 of the latch-bolt, so that when it is necessary to unlock or retract the lock-bolt, by turning the key in the opposite direction from that employed in locking, the arm 49^2 , again coming in contact with the notch O^2 , retracts both the lock and the latch-bolt. Before the key can be removed from the revolving plug the arm 49^2 comes in contact with the arm 7 ^{2} of the sliding fence 7, and withdraws the bent end 6 of said fence from the recess 5 of the latch-bolt and permits said latch-bolt to project again into its keeper. At the same time the sliding

plate comes in contact with the flange y^3 and releases the tumblers and permits the key to be withdrawn from the revolving plug.

Having described my invention, what I claim is—

1. In a cylinder-lock, the combination, with the cylinder-case, having the opening 47, and the revolving plug, of the slotted sliding plate, the lug thereon, and the tumblers engaging a slot in said plate, the said plate adapted to operate against the eccentric flange of a mortise-lock, substantially as specified.

2. In a cylinder-lock, the combination, with the case and the revolving plug, of the slotted plate seated in bevel grooves in the plug and having the key-slot, and the tumblers having the actuating-springs, substantially as specified.

3. The combination, with the cylinder-case having the central opening provided with a radially-disposed slot, of the revolving plug provided with the shouldered spring-pressed locking-pin supported in a seat therein and normally engaging said slot, the shouldered tumblers K , K' , K^2 , K^3 , and K^4 and their actuating-springs, the removable piece 150, the slotted plate having its slot registering with the radially-disposed slot in the cylinder-case, the projecting slotted sliding plate, and the projecting arm 49^2 , substantially as specified.

In testimony whereof I affix my signature in presence of two witnesses.

WILLIAM SHERWOOD FISKE.
